United States Patent Office

Des. 203,750
Patented Feb. 15, 1966

203,750

BASE FOR A TELEPHONE SET

Armistead Wharton, Henrietta, N.Y., assignor, by mesne assignments, to Stromberg-Carlson Corporation, Rochester, N.Y., a corporation of Delaware

Filed July 26, 1962, Ser. No. 71,058

Term of patent 14 years

(Cl. D26—14)

FIG. 1

FIG. 2

FIG. 3

FIG. 4

FIG. 5

FIG. 6

FIG. 1 is a perspective view of a base for a telephone set, showing my new design;

FIG. 2 is a top plan view;

FIG. 3 is a left side elevational view;

FIG. 4 is a front elevational view;

FIG. 5 is a right side elevational view; and

FIG. 6 is a rear elevational view thereof.

I claim:

The ornamental design for a base for a telephone set, substantially as shown.
